UNITED STATES PATENT OFFICE.

GEORGE L. WELLER, OF CHICAGO, ILLINOIS, ASSIGNOR TO KALMAN STEEL COMPANY, OF CHICAGO, ILLINOIS, A CORPORATION OF DELAWARE.

ROAD STRIP.

Application filed September 19, 1925. Serial No. 57,311.

My invention relates to metal strips adapted to be imbedded in a concrete roadway for the purpose of providing an expansion joint, and particularly to a novel end connection 5 for use in connection therewith.

It is customary in the construction of such strips to provide a longitudinal channel therein, intermediate the top and bottom; and at the point of junction of two strips to 10 overlap the same and pass a fastening pin through the interfitting channels. This, however, has the objection that the strip is not of uniform thickness continuously and involves difficulties in connection with the 15 formation of the groove provided at the wearing surface of the road at a point immediately above the upper margin of the strip.

In order to obviate the described difficulties, I have provided a construction in which the body portions of the strips may remain 20 in correct alignment and in which the same facilities as heretofore employed may be used for joining the adjacent ends of the strips. To that end I extend the channel portion of the strip at one end and off-set the 25 extended portion to the extent of the thickness of the metal, so that the extended portion of one strip may fit within the channel 30 of an aligned strip. In this manner I am able to secure all the advantages of an overlapped strip as well as the advantages incident to a construction in which the ends of the strip are abutted.

35 The invention will be more readily understood by reference to the accompanying drawings, in which;

Fig. 1 is a transverse sectional view 40 through a roadway in which the strip of my invention has been installed.

Fig. 2 is a sectional view on the line 2—2 of Fig. 1;

Fig. 3 is a perspective view of a pair of strips constructed in accordance with my 45 invention, and

Fig. 4 is a fragmentary perspective view of a slightly modified form.

In the drawings, it will be seen that I have 50 illustrated a roadway, 10, composed of concrete, an expansion joint being provided by the use of the strip of my invention. This strip as best shown in Fig. 3, comprises upper and lower marginal or body portions, 11, 12, respectively, and an intermediate V-shaped laterally off-set channel portion, 13,

extending longitudinally of the strip. At one end the channel portion is extended as at 14, and the extended portion is laterally off-set as at 15, to the extent of the thickness of the metal. The extended portion has 60 vertically aligned apertures, 16, registering with similar apertures in the opposite end of a co-operating strip in order to accommodate a pin, 17, shown in Fig. 1. Horizontal bars, 18, pass through the strip in the usual manner.

In assembling, the strips are placed end to end with the marginal portions, 11, 12, in abutting engagement, the extended portions, 14, of the strips entering the channels 70 and interfitting closely therewith. The top margins of the strip are below the finished level of the concrete, and when or after the concrete is cast, a groove is provided immediately above the strip which groove is subsequently filled with tar, 19, or similar material.

In the construction shown in Fig. 4, the strip is identical except that the extended portion is formed by providing a separate, 80 short section, 20, of such contour that it will fit within the V-shaped channel, 21, at one end of a strip, 22, and then welding it in position, as indicated at 23. Thus no lateral off-setting of the extended portion 85 is required, and a cooperating strip may be placed in abutting relation the same as heretofore described.

The improved strip will be found to be simple and economical to manufacture and 90 of increased facility in use. Modifications other than that already described may be made and I do not wish to be limited except as indicated in the appended claims.

I claim:

1. A road strip having a longitudinally extending, laterally off-set channel located intermediate its margins, said channel being extended beyond the end of the margins at one end, the extended portion being deflected inwardly to the extent of the thickness of the metal constituting the strip, whereby said extended portion may fit with in the channel of an adjacent strip and allow the top and bottom margins of the strip 105 to be positioned in end abutment and alignment.

2. A road strip having a longitudinally extending, laterally off-set channel located intermediate its margins, said channel be- 110

ing extended beyond the end of the margins at one end, the extended portion being deflected inwardly to the extent of the thickness of the metal constituting the strip, whereby said extended portion may fit within the channel of an adjacent strip and allow the top and bottom margins of the strip to be positioned in end abutment and alignment, said extended portion and the channel sides of an adjacent strip having registering apertures to accommodate a vertically extending pin.

3. A road strip having a longitudinally extending, laterally off-set channel, located intermediate its side margins, said channel being extended beyond the end of the margins at one end, the extended portion being positioned inwardly of the main por-

tion of the channel to the extent of the thickness of the metal of the strip. 20

4. A road strip having top and bottom parallel margin portions and an intermediate V-shaped laterally projecting channel portion, said channel portion being extended beyond the ends of the marginal portions 25 and having vertically registering apertures, said extended portion being laterally off-set relative to the corresponding portion that is a part of the body of the strip, whereby the marginal portions of two strips may 30 abut in alignment without overlapping, the overlapped portions of the channels being adapted to receive a vertical fastening pin.

In testimony whereof I have affixed my signature.

GEORGE L. WELLER.
